UNITED STATES PATENT OFFICE.

JOHN T. MCTARNAHAN, OF BOSTON, MASSACHUSETTS; BY OPERATION OF LAW TO
RALPH H. CAHOUET, TRUSTEE IN BANKRUPTCY OF MCTARNAHAN FUEL OIL
BURNING CORPORATION, OF BOSTON, MASSACHUSETTS, A CORPORATION OF MASSA-
CHUSETTS.

FUEL-OIL-BURNING APPARATUS.

Application filed December 22, 1922. Serial No. 608,503.

To all whom it may concern:—

Be it known that I, JOHN T. MCTARNAHAN, a citizen of the United States, residing at Boston, in the county of Suffolk and State of Massachusetts, have invented certain new and useful Improvements in Fuel-Oil-Burning Apparatus, of which the following is a specification.

The invention to be hereinafter described relates to fuel oil burning apparatus, and more particularly to the regulation of the supply of fuel oil to the burner or burners.

Fuel oil has a heavy viscous character which prevents the same from flowing freely at normal temperature, and its viscosity varies owing to lack of uniformity in the character of the fuel oil and variation in the normal temperature of the atmosphere.

For example, if fuel oil is fed under predetermined pressure through an orifice of a given size, heavy fuel oil will flow therethrough at a slower rate than lighter fuel oil.

The supply of fuel oil to the burner should be varied in accordance with the degree of heat required, and this may be accomplished by a regulating valve which is adjustable to provide an orifice of varying size through which the fuel oil may flow to the burner.

If this regulating valve is to serve to control the supply of fuel oil, it is essential that the viscosity of the fuel oil delivered to the valve should be uniform, and that the pressure forcing the fuel oil to the valve should be uniform.

One of the purposes of the present invention, therefore, is to provide means for automatically maintaining the temperature and the viscosity of the oil uniform, and means for automatically maintaining the pressure of the oil delivered to the regulating valve uniform.

The fuel oil regulating valve may be controlled by an automatic regulator, such, for example, as disclosed in my copending application Serial No. 588,418, filed September 15, 1922. This regulator is adapted to be operated in response to variations in the pressure of steam developed by a generator to so regulate the supply of fuel oil to the burner as to develop heat which will gener-

ate steam and maintain the same at substantially uniform pressure under varying load conditions. For example, if the pressure of the steam developed rises, the regulator is automatically operated to reduce the amount of fuel oil delivered to the burner, and on the other hand, if the pressure of the steam developed lowers, the regulator is automatically operated to increase the supply of fuel oil delivered to the burner. The mechanism is such that the supply of fuel oil is fed automatically to compensate for increase or decrease in pressure of steam developed by the generator, which in turn varies inversely with respect to the demand for steam developed by the generator.

The distance from the fuel oil supply tank to the burner varies in different installations and where several burners are used, the distances of the respective burners from the tank vary. The feed of the heavy fuel oil through the pipes to the burners produces substantial friction between the oil and the pipes, and the longer the pipes, the greater the amount of friction. It is desirable to provide means to compensate for this variation in friction. Another purpose of the invention, therefore, is to provide a valve between the automatic regulator and each burner which may be adjusted to compensate for this variation in the friction, and where several burners are used, the valves therefor may be adjusted so that the size of the fires therefrom may be equal. These valves may be set and remain as adjusted, so that during operation of the burner, there will be no need of manual adjustment or regulation of the fuel oil intermediate the automatic regulator and the firing point of the burner.

The character of the invention may be best understood by reference to the following description of one good form thereof shown in the accompanying drawings, wherein:

Fig. 1 is a view partly in section and partly in elevation of a boiler equipped with oil burning apparatus embodying the invention;

Fig. 1* is an elevation of burners and piping therefor;

Fig. 2 is a sectional view of a valve to be referred to.

Fig. 2^a is a diagram showing the shape of the ports of the valve shown in Fig. 2;

Fig. 3 is a vertical section through the temperature responsive means for controlling the supply of steam to the jacks-
ets for heating the fuel oil delivered to the regulating means and the burner, so as to maintain constant viscosity of the fuel oil;

Fig. 4 is a vertical section through the means responsive to the pressure of the fuel oil for controlling the supply of steam to the pump for forcing the fuel oil to the regulating means and to the burner, so as to maintain constant pressure of the oil de-
livered by the pump to the regulator valve;

Fig. 5 is a vertical section through one of the heaters for the fuel oil;

Fig. 6 is a view partly in section and partly in elevation of means for regulating the supply of oil and atomizing steam to the burner;

Fig. 7 is a side elevation of a portion of the mechanism shown in Fig. 6;

Fig. 8 is a view partly in elevation and partly in section showing the oil and steam regulating valves and means for adjusting the same; and

Fig. 9 is a plan of the mechanism shown in Fig. 6.

Referring to the drawings, and more particularly to Fig. 1, a boiler is shown therein of the well known Babcock & Wilcox type, comprising a drum 1 communicating with a front header 3 and a rear header 5, said headers being connected by inclined water tubes 7 provided with baffles 9 and 11. Beneath the water tubes is a combustion chamber 13 having a front wall 15 and a bridge wall 17. The gases of combustion leaving the combustion chamber cross and recross the inclined water tubes and leave the boiler through the flue 19 leading to the stack, said flue being provided with a damper 21 which may be automatically controlled by means to be described.

A fuel oil burner or burners such as the burner 23 may project through the front wall 15 of the combustion chamber, and deliver the fuel oil therein. This burner may be of well known construction, and therefore, it is unnecessary to show and describe the same in detail herein. The burner may be of the type in which an atomizing fluid such, for example, as steam is employed to break up and atomize the fuel oil delivered from the burner, or the burner may be of the mechanical type in which no atomizing fluid is required, the fuel oil being mechanically atomized.

The fuel oil for the burner may be taken from a suitable source of supply such, for example, as the storage tank 25. Suitable piping may be provided to conduct the fuel oil from the tank to the burner. In the present instance, a pipe 27 leads from the

tank to a steam pump 29 of well known construction and including a cylinder 31 for pumping the oil and a cylinder 33 for receiving steam for operating the piston in the pumping cylinder.

A pipe 35 leads from the cylinder 31 to a heater 37. This heater, in the present instance, comprises a pair of cylinders or jackets 39 receiving coils 41 (Fig. 5) having their lower ends connected by branch pipes 43 with the pipe 35, and having their upper ends connected by branch pipes 45 with a pipe 47 connected by a union 49 with a pipe 51 leading to the valve 53 of the regulator 55. The valve 53 in turn is connected by a pipe 57 to the burner 23.

To supply steam for operating the pump, the steam main 59 of the boiler may be connected by a pipe 61 with a pipe 63 leading to the steam cylinder 33 of the pump.

Suitable means may be provided responsive to the pressure of the fuel oil delivered by the pump automatically to control the supply of steam to the pump cylinder 33, thereby to regulate the pressure of the fuel oil fed to the regulating means 55 and to the burner 23. To accomplish this, a fitting 65 is interposed in the pipe 63, and contains a valve 67 (Fig. 4). This valve is connected by a stem 69 with a head 71 secured to a diaphragm 73 mounted in the casing 75 carried by a housing 77 supported on the fitting 65.

A coil spring 79 encircles the stem and is confined between the head 71 and a flange 81 on a sleeve 83 receiving the stem and threaded in a hole in a web 85 carried by the housing 77. At the lower end of the sleeve 83 is a boss 87 having holes 89 adapted to receive a suitable tool for adjusting the sleeve to vary the tension of the spring 79 as required. The upper end of the casing 75 is connected by a pipe 91 with the oil conducting pipe 35 leading from the pump, and therefore, subjects the upper side of the diaphragm 73 to the pressure of the fuel oil delivered through the pipe 35.

The construction is such that when the pressure of the fuel oil delivered through the pipe 35 rises, the diaphragm 73 will be flexed downward against the resistance of the coil spring 79, thereby moving the stem 69 downward to close or reduce the opening provided by the valve 67, and thereby shut off or reduce the amount of steam delivered to the pump cylinder 33. On the other hand, if the pressure of the fuel oil delivered by the pump through the pipe 35 falls, the pressure in the casing 75 above the diaphragm 73 will be reduced, thereby allowing the coil spring 79 to shift the stem 69 and the valve 67 upward so as to open said valve or increase the opening thereof, and increase the supply of steam delivered to the pump cylinder 33. The coil spring 79 may be adjusted

so that the pump will be operated to feed fuel oil from the tank to the regulating means 55 and to the burner 33 at the predetermined pressure desired.

5 The steam may be supplied to the fuel oil heater 37 by a pipe 93 leading from the steam pipe 61 referred to, to branch pipes 95 connected to the upper ends of the heater cylinders 39. The steam or condensation 10 may be conducted from the cylinders 39 through a pipe 97 to a trap 99 connected to a pipe 101 leading to a sump 103, a bypass 105 being provided for the trap.

15 Suitable means may be provided automatically to regulate the supply of steam to the heater cylinders 39. This means, in the present instance of the invention, comprises a fitting 107 (Fig. 3) interposed in the pipe 93 and containing a valve 109. This valve 20 may be connected by a stem 111 with a head 113 engaging the movable head 115 of the bellows-like diaphragm 117 mounted in a housing 119 mounted on the fitting 107.

25 A coil spring 121 is confined between the head 113 and a collar 123 resting on a hand nut 125 threaded on a sleeve 127 mounted on a web 129 carried by the housing 119. The upper head 115 of the diaphragm is connected to a pipe 131 leading to a thermostat 133 comprising a tubular bulb 135 mounted in the union 49 referred to, in the pipe 51 leading to the regulator 55. The tubular bulb projects downward through the union 49 and extends a substantial distance into the fuel oil conducting pipe 47, so that a substantial portion of the length of the tubular bulb may be surrounded by and subjected to the temperature of the fuel oil passing through the pipe 47.

35 40 Mounted in the tubular bulb 135 is a small tube 137 communicating with the pipe 131. The tubular bulb 135 may contain ether or other liquid which vaporizes instantly on a slight rise in the temperature of the fuel oil surrounding the bulb 135, and the latter is not filled with the liquid, but has a space 139 above the level of the liquid to allow the vapor to be compressed and create a pressure which is transmitted through the tube 137 and a pipe 131 to the diaphragm 117.

45 Therefore, as the temperature of the fuel oil surrounding the bulb 135 rises, the pressure in the diaphragm will force the head 50 55 113 downward against the resistance of the coil spring 121, thereby closing or reducing the opening of the valve 109 so as to cut off or reduce the supply of steam to the heater cylinders 37, and thereby reduce the heating effect in said cylinders and on the fuel oil conducting coils 41 in said cylinders.

60 On the other hand, when the temperature of the fuel oil in the pipe 47 lowers, the pressure in the diaphragm 117 will be reduced, thereby allowing the coil spring 121

to expand and open or increase the opening of the valve 109 so as to increase the supply of steam to the heater cylinders, and thereby increase the heating effect in the cylinders on the fuel oil conducting coils 41.

70

The hand nut 125 may be adjusted to vary the tension of the coil spring 121, so that the supply of steam to the heater may be regulated so as to maintain the temperature of the fuel oil delivered to the regulator 55 and the burner at the point desired. Thus, the predetermined viscosity of the fuel oil delivered to the regulator 55 may be controlled and maintained.

80 As stated, the regulator 55 may be substantially the same as disclosed in my said copending application.

This regulator comprises a pedestal 141 (Fig. 6) supporting a base 143 having an apron 145 depending therefrom at one side 85 of the pedestal, and having a plate 147 with arms 149 and 151 projecting laterally therefrom. One of these arms may support the oil regulating valve 53 referred to, and the other arm may support a valve 153 for regulating the supply of steam or other atomizing fluid delivered to the burner.

90 The oil regulating valve comprises a cylindrical casing 155 connected to the oil supply pipes 51 and 57. Mounted in the cylindrical casing 155 is a rotary sleeve valve 157 having opposed ports for communication with the pipes 51 and 57. The valve is fast on a stem 159 projecting through a stuffing box 161 on the head of the valve 100 casing, said stem being adapted to be rocked by means to be described for giving the valve rotative adjustment to cause the valve ports to turn with respect to the pipes 51 and 57, thereby to vary the effective openings of said ports and regulate the supply of oil.

100 To enable manual adjustment of the valve, a plug 163 is mounted in the sleeve valve and splined thereto. A stem 165 threaded in a bore in the plug extends through a stuffing box 167 on the valve casing, and the outer end of the stem is provided with a hand wheel 169. The construction is such that the hand wheel may 115 be manually rotated to adjust the plug longitudinally of the sleeve valve to vary the effective openings of the valve ports as required.

110 The valve 153 for controlling the supply of steam to the burner may comprise a cylindrical casing 171 connected to a pipe 173 leading from the steam supply pipe 61 referred to, said valve casing being also connected to a pipe 175 which leads to the 125 burner.

120 Mounted in the cylindrical casing 171 is a sleeve valve 177 having ports for communication with the pipes 173 and 175. The sleeve valve has a stem 179 secured thereto 130

projecting through a stuffing box 181 at one end of the cylindrical casing, said stem being adapted to be rocked by means to be described to give the sleeve valve rotative adjustment and vary the relation of the ports thereof with respect to the pipes 173 and 175 so as to regulate the supply of atomizing steam as required.

To enable manual regulation of the valve, 10 a plug 183 may be mounted in the sleeve valve and splined thereto. A stem 185 is threaded into the plug and projects through a stuffing box 187 mounted on a head of the valve casing, said stem having a hand wheel 189 thereon. The hand wheel may be rotated manually; thereby to move the plug longitudinally with respect to the sleeve valve so as to vary the effective openings thereof and regulate the supply of atomizing steam as required.

The means for automatically rotatively adjusting the valves comprises an elongated plate 191 (Figs. 7, 8 and 9) having a groove receiving a cross head 193. Projecting from 25 the cross head are lugs carrying an inclined guide 195 adjustably connected to said lugs by bolts 197 entered through elongated slots 199 in the terminals of the guide, the construction being such that the guide may be 30 set at different positions of angular adjustment.

Opposed to the guide 195 is a guide 201 having elongated slots 203 through which the bolts 197 project, the construction being 35 such that this guide may be set in different positions of angular adjustment.

Fast on the stem of the fuel oil regulating valve is a crank 205 provided with a roller 207 projecting into an elongated slot 40 209 of the guide 195.

Fast on the stem of the steam regulating valve is a crank 211 having a roller 213 projecting into an elongated slot 215 in the guide 205.

45 The construction is such that when the cross head is reciprocated by means to be described, the guides will slide relatively to the crank rollers, and thereby rock the fuel oil and steam valves to regulate the 50 supply of oil and steam to the burner.

To reciprocate the cross head, the rod 217 may have one end connected to the upper end of the cross head, and its opposite end connected to an arm 219 secured to the upper 55 end of the piston rod 221 connected to a piston 223 in a cylinder 225 mounted on a housing 227 supported on the base 143 referred to.

To move the piston 223 in the cylinder 60 225, a pilot valve 279 may have a pipe 281 for admitting hydraulic pressure thereto from any suitable source, and the pilot valve may have an exhaust pipe 283 to allow release of the hydraulic pressure.

65 To control the pilot valve, it may have a

stem 285 connected by a yoke 287 with the upper end of a rod 289, the lower end of which is pivotally connected to a beam or lever 291. An end portion of this lever projects into the housing 227, and has lugs 293 70 provided with knife edges for engagement with a forked bracket 295 secured to and projecting down from the top of the housing.

Mounted in the housing is a diaphragm 75 297 of rubber or other suitable flexible material, and having a button 299 provided with a knife edge on which rests the lower edge of the lever 291. Beneath the diaphragm is a steam pressure chamber 301 80 connected by a pipe 303 with the steam main 59 referred to. At a point set in somewhat from the outer end of the lever 291 is pivotally connected a rod 305 having a disk 307 at the lower end thereof for supporting a plurality of weights 309, the number of which may be varied according to conditions as required.

Mounted on the lever is a carriage 311 having wheels adapted to roll along the upper edge of the lever. A rod 313 depends from the carriage and serves to support a plurality of weights 315, the number of which may be varied. The carriage and weights carried thereby serve as a poise for 95 varying the effective pressure on the upper side of the diaphragm in opposition to the steam pressure on the under side of the diaphragm.

It is desirable that when the piston 223 100 is moved downward, the poise shall be moved inward on the lever, and when the piston is moved upward, the poise shall be moved outward on the lever, in order to compensate for variations in the steam pressure 105 on the under side of the diaphragm.

To accomplish this, in the present instance, a pair of arms 317 are secured to the piston stem 221, project laterally therefrom, and are connected to the upper ends 110 of rods 319 which extend downward along the cylinder at opposite sides of the pilot valve and at opposite sides of the lever. The lower ends of said rods are connected to a head 321, to which is secured the lower end 115 of a chain 323 which projects upward over a roller 325 carried by the housing 227, and the opposite end of the chain is connected to the poise. Also connected to the poise is a chain 327 which extends over a roller 120 329 carried by the outer end of the lever, and the opposite end of said chain is connected to a rod 331 carrying a plurality of weights 333, the number of which may be varied as required.

The regulator described may also serve to 125 vary the draft of the boiler in response to variations in the pressure of the steam developed by the generator. To accomplish this, the damper 21 referred to, may have 130

an arm 335 (Fig. 1) connected by a flexible member 337 with an eye 339 attached to the piston rod 221, said flexible member being guided by suitable rollers 341 and 343.

- 5 When the piston moves downward, it will rock the damper in one direction, and a weight 345 carried by the damper arm 335 will serve to rock the damper in the opposite direction on upward movement of the 10 piston, thereby automatically to regulate the draft in response to variations in the steam pressure operating through the diaphragm and the compensating mechanism to control the movements of the piston which is connected to the damper.

The operation of the regulating apparatus will be readily understood from the foregoing description thereof. If the pressure of the steam developed by the generator rises 20 above a desired predetermined steam pressure, the diaphragm will be flexed upward, thereby rocking the lever 291 upward. This movement of the lever will operate through the rod 289 and the yoke 287 to shift the 25 pilot valve to admit hydraulic pressure into the cylinder 225 at the under side of the piston 223. This will cause the piston to move upward, and the latter through its rod 221 and the rods 319, will pull up and let out the 30 chain 323 and enable the weights 333 to operate through the chain 327 and cause the poise to move outward on the lever, thereby increasing the pressure on the diaphragm and causing the latter to flex downward and 35 shift the pilot valve to cut off the supply of hydraulic pressure to the under side of the piston.

The upward movement of the piston will also operate through the rod 217 to move the 40 cross head 193 upward, thereby carrying the guides 195 and 201 upward, and owing to the obliquity of said guides, the cranks on the fuel oil valve and the steam valve stems will be given a rocking movement, thereby adjusting said valves so as to reduce the amount of oil and atomizing steam delivered to the burner.

On the other hand, if the pressure of the steam developed by the generator drops below the selected standard steam pressure, the 50 diaphragm will flex downward, and the lever 291 will rock downward, thereby shifting the pilot valve in a direction opposite to its previous movement to admit hydraulic pressure into the cylinder above the piston. This will cause the piston to move downward and draw the poise inward along the lever, thereby reducing the pressure on the upper side of the diaphragm and allowing 55 the steam pressure beneath the diaphragm to flex the latter upward and operate the pilot valve to cut off the supply of hydraulic pressure to the upper side of the piston.

The downward movement of the piston 60 will move the cross head downward, thereby

carrying the guides 195 and 201 downward, and owing to the obliquity of the latter, the cranks for the oil and steam valves will be rocked in a direction opposite to their previous movements, thereby to increase the 70 openings of the oil and steam valves so as to increase the amount of oil and steam delivered to the burner.

If the movement of the piston is not sufficient to vary the amount of fuel oil and 75 steam delivered to the burner, as required to return the steam pressure to the predetermined amount, the piston will progressively and gradually receive movements until the valves have been properly regulated 80 to bring the steam pressure to the predetermined pressure.

The means for automatically controlling the viscosity of the oil, and the means for 85 automatically controlling the feeding pressure of the oil, insure delivery of the oil to the regulating valve 53 under continued uniform conditions, so that variation in the opening of the oil regulating valve will reliably serve to control the regulation of the 90 fuel oil. The automatic regulation of the steam valve 153 will enable atomizing steam to be supplied to the burner in proper proportion to the oil delivered to the burner under the control of the oil regulating 95 valve 53.

It is desirable to provide valves between the regulator and the burner which may be set to provide orifices of predetermined size 100 through which the fuel oil and the atomizing steam may pass to the burner. To accomplish this, in the present instance of the invention, valves 347 and 349 (Fig. 1) are respectively interposed in the pipes 57 and 175, and since these valves are similar, a description of one will suffice for both.

These valves may each comprise a fitting 110 351 (Fig. 2) having a tapered bore 353 in which is fitted a tapered valve 355 having diametrically opposed diamond-shaped ports 357 therein cooperating with similarly shaped ports 358 in said fitting. Fast on the valve is a handle 359 provided with a pointer 361 adapted to move over a graduated dial 363.

The construction is such that on grasping the handle 359, the valve may be rotatively 115 adjusted to vary the effective openings of the diamond-shaped ports 357, and owing to the shape of these ports, a desirable nicety of adjustment may be obtained. The pointer and dial enable ready visualization of the adjustments of the valve and the size of the effective openings. When these valves have been 120 adjusted for certain conditions, they remain 125 set and should not be touched by the attendant, since the control of the supply of fuel oil and steam to the burner is automatically governed by the regulator which adjusts the oil valve 53 and the steam valve 153.

Referring to Fig. 1^a, a plurality of burners 365 are shown therein, one pair adapted to serve one boiler, and the other adapted to serve another boiler. The oil is conducted from the oil supply tank to said burners through a pipe 367 and branch pipes 369. Each of the branch pipes may be provided with a valve 371 which may be similar to the valve shown in Fig. 2, and each of said branch pipes may be provided with a usual valve 373 by which the supply of oil to the burner may be turned on or off as desired. The atomizing steam may be conducted to the burners through a pipe 375 leading from the boiler, and connected by branch pipes 377 with the burners. Each of these branch pipes may be provided with a valve 379 which may be similar to the valve shown in Fig. 2, and each of said branch pipes may be provided with a usual valve 381 by which the supply of steam to the burners may be turned on or off as desired.

The burners at the left of Fig. 1^a are more remote from the oil supply tank than the burners at the right of said figure. The consequence is that the oil fed to the burners at the left of said figure will experience more friction than the oil fed to the burners at the right of said figure. However, the valves 371 in the branch pipes leading to the burners may be adjusted to compensate for this variation in friction, so that the size of the flames issuing from the burners will be the same.

Similarly, the valves 379 in the branch pipes leading from the steam pipe may be relatively adjusted to compensate for the variation in friction of the steam delivered to the burners, so that the pressure of the steam and the atomizing effect thereof will be the same at all of the burners.

In some instances a mechanical burner or burners may be employed, that is, a burner which is constructed to break up or atomize

the fuel oil mechanically, and without the necessity of employing steam or other atomizing fluid.

It will be understood that the invention is not limited to the specific embodiment shown, and that various deviations may be made therefrom without departing from the spirit and scope of the appended claims.

What is claimed is:

1. Fuel oil burning apparatus comprising, in combination, a burner, means for conducting fuel oil from a source of supply to the burner, means for automatically regulating the amount of fuel oil delivered to the burner, and means for automatically regulating the temperature and pressure of the fuel oil delivered to the regulating means.

2. The combination with a boiler of a burner therefor, means for conducting fuel oil from a source of supply to the burner, means responsive to the pressure of steam developed by the boiler for automatically regulating the amount of fuel oil delivered to the burner, a heater for heating the fuel oil delivered to the regulating means, means to supply steam from the boiler to the heater, a valve for regulating the amount of steam delivered to the heater, and means for automatically controlling said valve including a thermostat having an element introduced into the path of the oil between the heater and the regulating means.

3. The combination with a boiler, of a burner, means for conducting fuel oil from a source of supply to the burner, means for automatically regulating the amount of fuel oil delivered to the burner, said regulating means being operable in response to the pressure of the steam developed by the boiler, and means for automatically maintaining uniform the temperature and pressure of the fuel oil delivered to the regulating means.

JOHN T. McTARNAHAN.
